(57) CLAIM

The ornamental design for underwear, as shown and described.

DESCRIPTION

FIG. 1 is a perspective view of underwear showing my new design;

FIG. 2 is a perspective view thereof with the closure flap shown in the open position;

FIG. 3 is a front elevation thereof;

FIG. 4 is a rear elevation thereof;

FIG. 5 is a left-side elevation thereof;

FIG. 6 is a right-side elevation thereof;

FIG. 7 is a top plan view thereof; and,

FIG. 8 is a bottom plan view thereof.

The broken lines shown in the drawings represent stitching in the fabric.
